COMBINED TELEPHONE HANDSET AND STAND

Henry Dreyfuss, South Pasadena, Calif., and Lionel W. Mosing, Springfield, and Robert E. Prescott, Rumson, N.J., assignors to Bell Telephone Laboratories, Incorporated, New York, N.Y., a corporation of New York

Filed Sept. 21, 1964, Ser. No. 81,797

Term of patent 14 years

(Cl. D26—14)

FIG. 1

FIG. 2

FIG. 3

FIG. 4

FIG. 5

FIG. 6

FIG. 7

FIG. 11

FIG. 12

FIG. 13

FIG. 14

FIG. 15

FIG. 1 is a perspective view of a combined telephone handset and stand, showing one form of our new design with the handset in place wherein the transmitter portion is faired into the body of the handset and the stand has a distinctly concave portion to accommodate the handset;

FIG. 2 is a perspective view of the form shown in FIG. 1 with the handset removed from the stand;

FIG. 3 is a side elevational view of the form shown in FIG. 1, to an enlarged scale, the opposite side being substantially a mirror image thereof;

FIG. 4 is a top plan view of the form shown in FIG. 1, to an enlarged scale;

FIG. 5 is an end elevational view of the form shown in FIG. 1, to an enlarged scale;

FIG. 6 is a perspective view of a combined telephone handset and stand, showing another form of our new design with the handset in place wherein the transmitter portion is faired into the body of the handset and wherein the stand includes a recessed area bounded by a pair of protruding lip members to accommodate the handset;

FIG. 7 is a perspective view of the form shown in FIG. 6 with the handset removed from the stand, to a reduced scale;

FIG. 8 is a side elevational view of the form shown in FIG. 6, the opposite side being substantially a mirror image thereof;

FIG. 9 is a top plan view of the form shown in FIG. 6;

FIG. 10 is an end elevational view of the form shown in FIG. 6;

FIG. 11 is a perspective view of a combined telephone handset and stand showing still another form of our new design with the handset in place wherein the transmitter portion is stepped above the level of the inner face of

the handset and wherein the stand includes a pair of side lip members to accommodate the handset;

FIG. 12 is a perspective view of the form shown in FIG. 11 with the handset removed from the stand;

FIG. 13 is a side elevational view of the form shown in FIG. 11, to an enlarged scale, the opposite side being substantially a mirror image thereof;

FIG. 14 is an end elevational view of the form shown in FIG. 11, to an enlarged scale; and

FIG. 15 is a top plan view of the form shown in FIG. 11 to an enlarged scale.

The dominant features of our design reside in the portion shown in solid lines on the drawing.

A portion of the connecting cord shown in broken lines has been omitted from some of the figures for convenience in illustration.

This application is a continuation-in-part of our pending application Serial No. D. 72,400, filed November 6, 1962, now abandoned.

We claim:

The ornamental design for a combined telephone handset and stand, substantially as shown and described.
